UNITED STATES PATENT OFFICE.

EDWARD ELIAS VON TELL, OF GOTTERBORG, SWEDEN.

SHIP'S HATCH.

Application filed January 13, 1923. Serial No. 612,392.

To all whom it may concern:

Be it known that I, EDWARD ELIAS VON TELL, of Gottenborg, Sweden, Swedish subject, have invented certain new and useful 5 Improvements in and Relating to Ships' Hatches, of which the following is a specification.

This invention relates to ships' hatches and has for its object to provide an improved 10 construction and arrangement of hatches designed to facilitate the operations of lifting and lowering the hatches for opening and closing the hold of a vessel and to render the hatches secure against unauthorized or 15 accidental lifting after they have been brought into their closed position.

The improved construction and arrangement of ships' hatches according to the present invention comprises a pair of hatch members, which may have similar or dissimilar 20 dimensions, hinged at their adjacent edges to a beam or bar of any suitable material and cross sectional profile in such a manner that the free edges of the hatch members 25 can fold downwards but not upwards from the horizontal or closed position of the hatch, said beam being adapted to be engaged by the lifting tackle of a derrick or the like lifting device to lift the pair of hatch members 30 at their adjacent edges in order to open the ship's hold, thus allowing the two hatch members to swing inwards upon their hinges, and to fold together on being lifted clear 35 of the hatch coaming, whereupon they can be swung to one side and deposited on the deck, if desired, while in order to close the hold the folded pair of hatch members is brought over the hold and lowered, the depending 40 free edges of the hatch members first engaging the hatch coaming and being then separated to enable these edges to slide apart upon the hatch coaming under the action of the weight of the parts, until the said hatch members come into the closed position forming 45 a single rigid hatch which is thus locked in its closed position by its own weight alone.

In order that the nature of the invention may be clearly understood one way of carrying out the same will now be described with 50 reference to the accompanying drawings in which Fig. 1 is an end view of the two hinged hatch members resting with their lower edges upon the hatch coaming;

55 Fig. 2 is a similar view showing an arrangement for separating the lower edges of

the depending hatch members when being lowered into closed position;

Fig. 3 is a similar view showing the hatch members in completely closed and self-locking position;

Fig. 4 illustrates a detail.

Referring to the drawings, two hatch members 1 and 2 are shown hinged to an inverted iron T-beam 3, the hatch member 1 being somewhat narrower than the hatch member 2 for a purpose hereinafter referred to. This connection may conveniently be effected, for example by means of a hinge plate 4 fixed to the horizontal member of 70 the T-beam having ears 5 and 6 pierced with holes for hinge pins 7 and 8 passing through similar ears on hinge plates 9 and 10 fixed to the hatch members 1 and 2 respectively.

In the arrangement shown the hatch members are of wood but they may instead be made of any suitable metal or other material. Two holes are provided in the vertical member of the T-beam 3 at about equal distance from the ends of the beam, and preferably shackles such as shown at 12 in Figs. 1, 2, and 4 are pivotally connected to the beam by pins passing through the said holes to enable the hooks, such as shown at 11 at the depending ends of the slings 13, to be hooked into the said shackles for the purpose of lifting the beam and the hatch members. If desired however the hooks 11 may be passed directly into the holes in the vertical member of the beam and the shackles 80 12 be dispensed with, as shown in Fig. 3. In this case the hatch members 1 and 2 are notched or cut away, as shown at 15 and 16 respectively in Fig. 3, in order to enable the hooks 11 to be passed into the said holes 85 when the hatches are in closed position.

The advantage of using the shackles 12 consists in the fact that the hooks 11 are thereby held more securely in operative position than when they are inserted directly into the holes in the beam 3. The shackles can conveniently be folded down out of the way into the position shown on the right in Fig. 4 in which the web of the shackle 12 enters a notch or groove 14 90 formed for the purpose in the vertical member of the beam 3.

In the closed position of the parts the inner edges 17 and 18 of the hatch members 1 and 2 respectively are located close to and 110 on opposite sides of the vertical member of the T-beam 3 as seen in Fig. 3, so that

in that position it is impossible to swing the hatch members upwards round their hinges.

Preferably the outer corners of the hatch members 1 and 2 are provided with iron or other metal protecting plates 19 as shown on the left of Fig. 3, and to the undersides of the said hatch members transverse bars 20 and 21 may be attached so as to engage one another in the raised and folded position of the hatches and thus prevent the latter from swinging inwards beyond the vertical position. In the arrangement illustrated channel bars are employed for this purpose.

In order to raise and open the hatches from the closed position of the same shown in Fig. 3 the hooks 11 on the end of slings 13 are inserted in the appropriate holes provided in the vertical member of the T-beam 3, or are passed into the shackles 12. The hook 22 at the end of the lifting tackle of the ship's derrick or the like power-operated lifting device is passed into the ring 23 connecting the slings 13 and the engine or motor is started. The T-beam 3 is vertically raised and the hatch members 1 and 2 hinged thereto commence to fold inwards towards one another. By continuing to lift, the hatch members are first brought into their vertical position and are then raised completely clear of the hatch coaming; they can now be swung to one side and be lowered on to any convenient part of the deck.

In closing the hatches the slings 13 and hook 22 are applied as before and the hatches are brought by means of the derrick or the like lifting device immediately over the centre part of the hold and are lowered into the position shown in Fig. 1 with the lower edges of the depending hatch members resting upon the hatch coaming. In order to facilitate the operation of separating the said lower edges of the hatch members 1 and 2 any convenient device may be employed. In one arrangement which has been found very convenient an additional sling 24 is applied in the manner shown in the drawings. At the lower end of the said sling a flat hook 25 is secured which is passed into engagement over the lower edge of the narrower hatch member 1, while the hook or ring 26 at the upper end of the sling 24 is brought into lifting engagement with the hook 22 of the lifting tackle. The additional sling 24 is applied in this manner when the hatch members 1 and 2 have been lowered into a position somewhat as shown in Fig. 1 in which the said hatch members are supported upright, or approximately so, upon the hatch coaming. The hook 22 is then lowered sufficiently to enable the hook 25 of the additional sling 24 to be passed over the lower edge of the hatch member 1, in the arrangement shown, the

slings 13 being slackened up in this operation as can be seen in Fig. 1. After passing the hook 25 over the said lower edge of the hatch member 1, the engine or motor is again started in the direction for lifting. The additional sling 24 becomes taut and takes the weight of the hatch member 1, lifting the same so as to separate the lower edge from that of the other hatch member 2 sufficiently to enable the said lower edges to slide apart by the action of their own weight when being lowered. The engine or motor is now reversed to lower, whereupon the lower edges of the hatch members engage the coaming and slide apart thereon under the action of the weight of the parts as shown in Fig. 2 in which the slings 13 are somewhat inclined to the vertical. Before the hatch members reach the completely closed position the sling 24 becomes slack and must be disengaged from the hatch member 1. The lowering is then continued until the hatches assume the completely closed position shown in Fig. 3. By lowering the hook 22 slightly beyond said closed position the slings 13 become slack and can be disengaged.

The hatch members 1 and 2 are now in their completely closed and locked position and cannot be raised by leverage under any part of their outer edges but can only be raised by applying power to the central T-beams. Thus the hatches automatically lock themselves by means of their own weight and it is only necessary to adopt measures for preventing the unauthorized use and handling of the ships' derrick or other lifting device in order to prevent the hatches from being opened at any time other than when ordered. It is also pointed out that the improved construction affords considerable economy of space owing to the hatches, when lifted for opening the hold, automatically folding together and only requiring a comparatively narrow space to accommodate them on deck.

What I claim and desire to secure by Letters Patent is:—

1. Construction of ships' hatches, comprising the combination with a pair of hatch members, of a beam, hinges connecting the adjacent edges of the hatch members to the beam arranged to allow the hatch members to fold downwards when the beam is lifted, but not to allow the hatch members to fold upwards above the closed position of the hatch members, and means for enabling a lifting device to engage with the beam for lifting, removing, and lowering the hinged pair of hatch members to open and close the hold of the vessel.

2. Arrangement of ships' hatches, comprising a pair of hatch members hinged at their adjacent edges to a beam, means on the beam for engaging with a lifting device

to lift the beam and attached hatch members to allow said members to fold inwards to open the hold of the vessel, and means for separating the lower edges of the depending hatch members when lowering said members into position on the hatch coaming to close the hold of the vessel.

3. In ships' hatches, the combination with an inverted T-beam, of a pair of hatch members hinged to the horizontal part of the beam, one hatch member to one edge and the other hatch member to the other edge of said horizontal part of the beam, the adjacent edges of the hatch members being arranged to abut against the opposite sides of the vertical part of the beam when the hatches are in the closed position, and openings in the said vertical part of the beam to receive the hooks of a sling for engagement by a lifting device.

4. In ships' hatches, the combination with an inverted T-beam, of a pair of hatch members hinged to the horizontal part of the beam, one hatch member to one edge and the other hatch member to the other edge of said horizontal part of the beam, the adjacent edges of the hatch members being arranged

to abut against the opposite sides of the vertical part of the beam when the hatches are in the closed position, and shackles secured to the said vertical part of the beam to receive the hooks of a sling for engagement by a lifting device.

5. In ships' hatches, the combination with an inverted T-beam, of a pair of hatch members hinged to the horizontal part of the beam, one hatch member to one edge and the other hatch member to the other edge of the said horizontal part of the beam, one hatch member having a smaller width than the other hatch member, the adjacent edges of the hatch members being arranged to abut against the opposite sides of the vertical part of the beam when the hatches are in the closed position, means on the said vertical part of the beam for engagement by a lifting device, and means for separating the lower edge of the hatch member having the smallest width from the lower edge of the other hatch member when lowering the hatches into closed position.

In testimony whereof I affix my signature.

EDWARD ELIAS VON TELL.
